The ornamental design for an electronic cigarette rod, as shown and described.

DESCRIPTION

FIG. 1 is a front view of an electronic cigarette rod of the present application;

FIG. 2 is a rear view of the electronic cigarette rod in FIG. 1;

FIG. 3 is a left view of the electronic cigarette rod in FIG. 1;

FIG. 4 is a right view of the electronic cigarette rod in FIG. 1;

FIG. 5 is a top view of the electronic cigarette rod in FIG. 1;

FIG. 6 is a bottom view of the electronic cigarette rod in FIG. 1;

FIG. 7 is a perspective view of the electronic cigarette rod in FIG. 1; and,

FIG. 8 is an enlarged bottom view of the electronic cigarette rod in FIG. 1.

The dotted lines in FIGS. 6-8, illustrating chamfers of holes, and the elongated dashed lines in FIGS. 1-5 and 7, illustrating an outer sleeve of an atomizer as an environmental structure, form no part of the claimed design.
